DESIGN FOR A RESILIENT INSERT FOR SHOES

Meyer Margolin, Elgin, Ill.

Application April 24, 1940, Serial No. 91,895

Term of patent 14 years

To all whom it may concern:

Be it known that I, Meyer Margolin, a citizen of the United States, residing at Elgin, in the county of Kane and State of Illinois, have invented a new, original, and ornamental Design for a Resilient Insert for Shoes, of which the following is a specification, reference being had to the accompanying drawing, forming a part thereof.

Figure 1 is a top plan view, slightly in per-

spective of a resilient insert for shoes, showing my new design; and

Figure 2 is a bottom view of the same, slightly in perspective.

The essential features of my design reside in the parts shown in full lines.

I claim:

The ornamental design for a resilient insert for shoes, substantially as shown and described.

MEYER MARGOLIN.
